UNITED STATES PATENT OFFICE

DENIS MACHELL HOLLINS, OF BLACKBURN, ENGLAND, ASSIGNOR TO DRAPER CORPORATION, OF HOPEDALE, MASSACHUSETTS, A CORPORATION OF MAINE

WEFT-FEELER MECHANISM FOR LOOMS FOR WEAVING

Application filed March 1, 1929, Serial No. 343,673, and in Great Britain March 2, 1928.

The invention relates to mechanism employed in looms for weaving to detect substantial exhaustion of the weft in a shuttle and, on such detection, to initiate stoppage of the loom for replenishment of the weft either by substituting a full bobbin for the substantially exhausted bobbin in the shuttle, or by replacement of the shuttle by one containing a full bobbin.

Two general classes of weft detector or feeler mechanism have hitherto been generally employed, one depending upon mechanical action and the other upon electric action.

Both these types of feeler mechanism have been open to objection. In the purely mechanical type of mechanism, the mechanical connections necessary to convey the indications of substantial weft exhaustion to the loom stopping or weft replenishing mechanism have had to be taken into account in locating the feeler on the loom, and have sometimes rendered it difficult or impossible to locate the feeler in the position desired, and such mechanical connections have also given rise to undesirable lost motion between the feeler and the stopping or replenishing mechanism. In the purely electric type of feeler mechanism, as usually constructed, it has been necessary to provide the bobbin with a metal sleeve with which, on substantial exhaustion of the weft, the end of the feeler spindle or a part carried thereby may be brought into contact as the lay beats up in order to complete an electric circuit through the feeler spindle.

When a feeler of the electric type just referred to is used with fine yarns, there is a liability that the weft may be cut by the contact of the detecting member with the last few turns of weft overlaying the sleeve, and cause thereby a stoppage of the loom. A further disadvantage appertaining to the use of an electric feeler of this type is that it necessitates the use of special bobbins which, owing to the metallic sleeves, are considerably more costly than the ordinary bobbins.

Attempts have been made to provide feeler mechanisms which are partly mechanical and partly electrical in their action, but these

have depended upon impact, between a movable member and the yarn mass on the bobbin, in order that when substantial exhaustion occurs the movable member may penetrate to the surface of the bobbin and be given by the latter such a movement as will complete an electric circuit for the purpose of initiating loom stoppage or weft replenishment.

The general object of the present invention is to provide an improved form or construction of weft feeler mechanism which, whilst being primarily mechanical in its action and having no detrimental effect upon the weft, will transmit its indications of weft exhaustion by electrical means and thus avoid any lost motion in its connections to the stop or change mechanism, whilst at the same time permitting of the feeler being disposed in any desired position. A further object is to so construct the mechanism as to facilitate the accurate adjustment which is requisite to efficient operation.

Feeler mechanism according to the invention is characterized in that a mechanical feeler of the known "side-slip" type, but of improved construction as compared with those hitherto employed, is arranged, by its side-slip action or movement when weft exhaustion is detected, to complete an electric circuit and to transmit thereby to stop or change mechanism an indication of such exhaustion.

The accompanying drawing illustrates in plan view at Fig. 1 a feeler mechanism according to the invention with the lid or cover of the enclosing casing removed, the parts being shown in the normal running positions.

Fig. 2 is a similar view to Fig. 1, but shows the parts in the positions they assume when substantial exhaustion of weft has been detected.

Referring to the drawing, *a* represents a box or casing adapted to be supported either on the moving part of the lay or on the breast beam according to the type or construction of loom concerned.

Within this casing there is pivotally mounted at *b'* a lever or arm *b* arranged to swing in a horizontal plane and longitudi-

nally of the loom. On this lever *b* there is mounted, to slide in a direction frontwardly and rearwardly of the loom, a feeler member *c* which is slidably mounted in bearings in flanges *b*², *b*⁴, on the lever *b*. The rear end of this member is preferably in the form of a flat plate *c*' of suitable width, having its rear extremity *c*² serrated or otherwise fashioned to form a weft-engaging surface. The portion *c*' of the feeler member is offset a short distance from the centre line of the body *c* and shank *c*³, and the latter are themselves offset from the centre line of the lever *b*. A coiled spring *c*⁴ confined on the shank *c*³ between a shoulder on said feeler and the flange *b*³ on the lever *b*, acts to hold the feeler member normally in a rearwardly projected position. The stops *b*² and *b*³ are shown as being constituted by upturned lugs on the lever *b*, and they form guides through which the body and the shank can respectively slide.

A rod *d*, mounted on the casing *a* to slide in a direction frontwardly and rearwardly of the loom, has its rear end fashioned to form, or to carry, an abutment *d*' which, as the lay beats up, is adapted to be struck by a convenient part *d*² on the lay, such as a part of the shuttle or of the shuttle box wall. This assumes that the feeler mechanism is mounted on the breast beam. A counter balancing spring *e*, confined between the front end of the casing *a* and an adjustable stop on the rod *d*, normally holds said rod projected rearwardly. The stop may take conveniently, and is shown as taking, the form of the boss *f*' of a member *f*, said boss being located on a threaded portion of the rod.

The end of the member *f* is forked as at *f*², and is arranged to straddle a horizontal spindle *g*, journaled at its ends in the casing *a* and passing through an opening in an upstanding lug *b*⁴ on the pivoted arm *b*, said lug being, as shown, offset from the pivot centre of the arm. An arm actuating spring *h*, confined between the lug *b*⁴ and a stop *h*', adjustably positioned on the spindle *g*, tends to swing the arm *b* towards the right in Fig. 1, but is restrained normally from so doing by the action of the counterbalancing spring *e*, which is of suitable greater strength than the spring *h*.

A lug *b*⁵, upstanding from the arm *b*, carries a spring blade or plate *i*, which is suitably insulated from the lug and has mounted upon it two contacts *i*' and *i*² which, when the arm is swung towards the right, as shown in Fig. 2, are adapted to be carried into abutment with two fixed contacts *j*' and *j*², mounted on an insulating block *k* secured to the casing *a* and connected by respective leads *m*' and *m*² to an electro-magnet or other device forming part of or included in an electric circuit controlling the actuation of the

weft change mechanism or stop mechanism of the loom.

If, as the lay beats up, a working quantity of weft is present on the bobbin, as indicated in Fig. 1, the feeler member is engaged by the weft mass and, as the lay completes its movement, is slid frontwardly. The rear end of the rod *d* is then engaged by its co-operating abutment and the rod is moved frontwardly, carrying the member *f* frontwardly away from the lug *b*⁴ on the lever *b*, but the engagement of the surface *c*² of the feeler member with the weft mass prevents the spring *h* from operating to swing the lever *b*.

If the weft supply is substantially exhausted, then when the feeler member has been moved forwardly by contact with the denuded bobbin *B* and the rod *d* has been moved by contact with its abutment, the feeler member will not be held by the weft mass against swinging movement, and the spring *h* will operate to swing the lever *b*, and with it the feeler member, to the right and thus carry the contacts *i*', *i*² into abutment with the fixed contacts *j*', *j*². The electric circuit is thus completed through the contacts *j*', and *j*² and the stop or weft change mechanism put into action.

As the lay goes back, the counterbalancing spring *e* acting on the rod *d* overcomes the arm-actuating spring *h* acting from the arm *b*, with the result that the latter, and with it the feeler member, is swung back to normal position, this being conveniently determined by the abutment of the feeler lever against a projection *a*' on the casing.

It will thus be seen that I have provided a sideslip feeler of simple construction which owing to the relatively broad weft engaging surface permissible will not damage or cut the weft, and that I utilize the lateral or side-slip movement of the feeler member to close directly an electric circuit governing the actuation of the weft change or stop mechanism of the loom. During such time as an ample supply of weft is present, the feeler member is subjected to no lateral urge until it has fully engaged the weft mass, but as substantial exhaustion approaches the feeler member is subjected to lateral urge as its engaging surface approaches the bobbin, so that if an insufficient weft supply is present the feeler may swing laterally and initiate electrically a weft change or a stoppage of the loom. Adjustment of the feeler action is effected simply by turning in one or the other direction the sliding rod *d* and the horizontal spindle *g* to vary the pressure of the springs respectively mounted thereon, that on the spindle ensuring closing of the electric circuit on a lateral or "side-slip" movement of the feeler, and that on the sliding rod ensuring return of the feeler lever to normal position.

It will be apparent that various changes may be made in the construction and arrangement of the parts employed in carrying out the invention, the essential feature being the employment of a mechanically operating feeler, of the general construction described, arranged to initiate by electrical means a weft change or stoppage of the loom upon indication of substantial weft exhaustion.

Having thus described my invention, what I claim as new and desire to secure by Letters Patent is:—

1. A feeler for looms comprising a casing, a feeler arm pivotally mounted thereon, a feeler yieldably mounted on said feeler arm and having means to engage the weft upon a bobbin, a spring mounted on said casing engaging said arm and tending to swing the same laterally, a counter-balancing spring mounted on said casing and acting normally to overcome the force of the spring acting upon the pivoted feeler arm, means acting upon each beat-up of the lay to relieve the force of said counter-balancing spring, thereby permitting said feeler arm-actuating spring to swing said feeler arm laterally upon detection of exhaustion of filling, and means operable by the lateral movement of said feeler arm to complete an electric circuit operable to effect a change in the operation of the loom.

2. A feeler for looms comprising a casing, a feeler arm, pivotally mounted thereon, a spring-actuated feeler slidably mounted on said feeler arm having means to engage the weft upon a bobbin and movable in a direction out of alignment with the pivot of said feeler arm, a spring mounted on said casing and engaging said arm tending to swing said arm laterally, a counter-balancing spring mounted on said casing in substantial parallelism with the spring acting upon said pivoted feeler arm and acting normally to overcome the force thereof, means acting upon each beat-up of the lay to relieve the force of said counter-balancing spring, thereby permitting said feeler arm-actuating spring to swing said feeler arm laterally upon detection of exhaustion of filling, and means operable by the lateral movement of said feeler arm to complete an electric circuit operable to effect a change in the operation of the loom.

3. A feeler for looms comprising a pivotally mounted feeler arm, a feeler yieldably mounted thereon having means to engage the weft upon a bobbin, an abutment on said feeler arm, a spring acting upon said abutment tending to swing said feeler arm laterally, a counter-balancing spring acting upon said abutment, and means operable upon each beat-up of the lay to relieve the force of said counter-balancing spring upon said abutment, thereby permitting said arm-

actuating spring to swing said feeler arm laterally upon detection of exhaustion of filling, and means operable by the lateral movement of said feeler arm to complete an electric circuit operable to effect a change in the operation of the loom.

4. A feeler for looms comprising a pivotally mounted feeler arm, a feeler yieldably mounted thereon having means to engage the weft upon a bobbin, an abutment on said feeler arm, a spring acting upon said abutment tending to swing said feeler arm laterally, a counter-balancing spring acting upon said abutment, means for adjusting the relative forces of said springs upon said abutment, and means operable upon each beat-up of the lay to relieve the force of said counter-balancing spring upon said abutment, thereby permitting said arm-actuating spring to swing said feeler arm laterally upon detection of exhaustion of filling, and means operable by the lateral movement of said feeler arm to complete an electric circuit operable to effect a change in the operation of the loom.

5. A feeler for looms comprising a casing, a feeler arm pivotally mounted upon said casing, a feeler yieldably mounted on said arm having means to engage the weft upon a bobbin, an abutment on said feeler arm, a feeler arm-actuating spring and a counter-balancing spring arranged in substantial parallelism and having means acting upon opposite sides of said abutment, and means acting upon each beat-up of the lay to relieve the force of said counter-balancing spring upon said abutment, thereby permitting said feeler arm-actuating spring to swing the feeler arm laterally upon detection of exhaustion of filling, and means operable by the lateral movement of said feeler arm to complete an electric circuit operable to effect a change in the operation of the loom.

6. A feeler for looms comprising a casing, a feeler arm pivotally mounted in said casing, a feeler yieldably mounted on said arm having means to engage the weft upon a bobbin, an abutment on said arm located in proximity to the pivot thereof, a spindle mounted in said casing having a screw threaded end portion with a nut mounted thereon, an arm-actuating spring intermediate of said nut and said abutment, a rod slidably mounted in said casing having means to engage a part carried by the lay and having a screw threaded portion provided with a nut, a member having one end engaging the abutment on said arm and its opposite end mounted upon said rod and engaging the nut thereupon, a counter-balancing spring intermediate of said member and said casing acting normally to hold said rod in forwardly extending position and to hold said member in engagement with said nut and to overcome the force of said arm-actuating spring.

whereby said feeler will be maintained normally in position to engage the weft upon a bobbin, but upon substantial exhaustion of filling by the engagement of said rod with the member upon the lay upon beat-up will cause a compression of said counter-balancing spring, thereby permitting said arm-actuating spring to cause lateral swinging movement of said arm, and means operable by the lateral movement of said arm to complete an electric circuit operable to effect a change in the operation of the loom.

7. A feeler for looms comprising a casing, a feeler arm pivotally mounted in said casing, a feeler yieldably mounted on said arm having means to engage the weft upon a bobbin, an abutment on said arm located in proximity to the pivot thereof, a spindle mounted in said casing having a screw threaded end portion with a nut mounted thereon, an arm-actuating spring intermediate of said nut and said abutment, a rod slidably mounted in said casing having means to engage a part carried by the lay and having a screw threaded portion provided with a nut, a member having one end engaging the abutment on said arm and its opposite end mounted upon said rod and engaging the nut thereupon, a counter-balancing spring intermediate of said member and said casing acting normally to hold said rod in forwardly extending position and to hold said member in engagement with said nut and to overcome the force of said arm-actuating spring whereby said feeler will be maintained normally in position to engage the weft upon a bobbin, means for rotating said rod to adjust the nut thereon and thereby to adjust the force of said counter-balancing spring.

40 In testimony whereof I affix my signature.
